ROLL-ON ENDORSE INK WELL

Filed Jan. 10, 1961

Fig. 6

Fig. 1

The diagram illustrates a vertical filter assembly. On the left, a rectangular frame is labeled with the number 32. A circular component, labeled 10, is attached to the top edge of the frame. A vertical tube, labeled 40, is inserted into the frame. The tube has a flared end at the bottom, labeled 28. A hatched area, labeled 44, is shown on the right side of the tube. The tube is labeled with the number 40 again at its top. A label 34 is positioned to the right of the tube. The bottom of the tube is labeled 12. A label 46 is located on the left side of the tube. A label 42 is located on the left side of the frame. A label 14 is located on the top edge of the frame. A label 50 is located at the top center of the frame. A label 36 is located on the right side of the frame. A label 24 is located on the right side of the frame. A label 4 is located on the left side of the frame. A label 4 is located on the right side of the frame. A label 16 is located on the bottom right of the frame.

ROLL-ON ENDORSE INK WELL

Martin Siegel, Livonia, Mich., assignor to Burroughs Corporation, Detroit, Mich., a corporation of Michigan Filed Jan. 10, 1961, Ser. No. 81,816 1 Claim. (Cl. 101—364)

This invention relates generally to ink applicators for printing apparatus and particularly to ink cartridges.

One of the objects of my invention is to provide an improved ink applicator for applying ink onto an inking roller.

Another object of the invention is to provide an improved ink cartridge and wick therefor in which the need for enclosing and sealing off the projecting end of the wick, such as with a rip-off cap, is eliminated without the usual accompanying vaporization of the ink.

Another object of the invention resides in the construction of the cartridge to support wick locating and retaining elements for preventing displacement of the wick in any direction.

A further object of the invention resides in the provision of an ink applicator of the above mentioned character in which the projecting wick end portion is displaced or reduced volumetrically in a confining wick passage to decrease the capillary action and to seal the passage against leakage should the applicator be tilted or turned over during its handling or storage.

Other objects of the invention will become apparent from the following detail description, taken in connection with the accompanying drawing in which:

FIG. 1 is an end view of an ink applicator embodying features of my invention;

FIG. 2 is a plan view partly broken away and in section;

FIG. 3 is a horizontal sectional view, taken along the line 3—3 of FIG. 1;

FIG. 4 is a cross sectional view, taken along the line 4—4 of FIG. 2;

FIG. 5 is a plan view of the top wall of the cartridge shown removed therefrom, and

FIG. 6 is a fragmentary plan view of a wick, shown removed from the ink applicator.

Referring to the drawing by characters of reference, the ink applicator shown comprises, in general, an ink cartridge or container 10 and a wick 12. The wick 12 has an end portion 14 that projects out of the cartridge 10, to apply ink, for example, to the surface of a roller 16. In the illustration of FIG. 1, the roller 16 is an ink distribution roller for distributing the ink over the surface of an inking roller 18 which in turn applies the ink to the print elements of a print wheel 20.

The cartridge 10 is box-like in construction having a bottom wall 22, side walls 24 and 26, end walls 28 and 30 and a top wall 32. Preferably the cartridge 10 is made of a plastic material or thermo-setting resin of sufficient degree of transparency to allow visual inspection of the quantity of ink remaining in the cartridge. The top wall 32 of the cartridge 10 is made separately from the cartridge proper, as a cover, and is cemented to the upper edges of side walls 24, 26, and end walls 28, 30, after the wick 12 is placed in proper position within the cartridge. Any suitable cement, such as any of the well-known resin

2

cements, may be employed to secure and seal the top wall 32 to the cartridge side and end walls.

The wick 12 is of rectangular shape in cross section and extends from the cartridge bottom wall 22 upwardly along the side wall 26 and out of the cartridge through the top wall 32, as shown in FIG. 4. In the edge of top wall 32, adjacent side wall 26, there is provided a recess 38 to receive the upper end portion 14 of the wick. Projecting upwardly from the top wall 32 and extending along the recessed edge thereof is a wick retainer member or flange 46 and on the other side of the wick there is provided an upstanding wick back-up member 36 which is preferably formed as an extension of the cartridge side wall 26. The back-up member 36 fits snugly into the recess 38 defined by the recessed top wall 32 and the retainer member 46 so as to form a wick restricting passage 34, the wick being tightly clamped and constricted between the retainer member 46 and back-up member 36 as shown in FIG. 4 to decrease the porosity of the wick and thus the capillary action, so as to avoid the application of an undesirable excess of ink to the roller 16. Displacement of the wick by clamping it, as above described, also seals the wick restricting passage 34 in the sense that ink will not leak out of said passage in the event that the cartridge is turned over in handling.

The back-up member 36 terminates just below the upper end of the wick 12 and gives support to the otherwise flexible wick to keep the upper end 14 thereof in contact with the periphery of roller 16. The back-up member 36 terminates at its opposite ends inwardly of the cartridge end walls 28, 30 respectively, and fits snugly between the ends, as at 40, of the wick restricting passage 34.

Integral with the recessed edge 38 of the top wall 32 there is a pair of horizontally spaced locators or pins 42 which extend respectively through a pair of apertures 44 provided in the wick 12 whereby to locate the wick both horizontally and vertically and hold the wick against accidental displacement in any direction.

In constructing the ink applicator, cement is applied to the upper edges of the cartridge side walls 24, 26, and end walls 28, 30, and the locating pins 42 are then inserted in the wick holes 44. By the use of a suitable clamping fixture, the top wall 32 is forced to the right, facing FIG. 4, to clamp the wick end portion 14 against the back-up member and held down against the upper edges of the side and end walls of the cartridge until the cement sets.

An air inlet or hole 48 is provided in the top wall 30 for entrance of air into the cartridge to induce the well-known capillary attraction required for passage of the ink up to the exposed end of the wick 12. Until the cartridge is placed in use, a closure member, such as a screw 50 may be used to close and seal the air inlet 48.

While I have shown and described my ink applicator in considerable detail, it will be understood that many variations and changes may be made therein without departing from the spirit and scope of the invention.

What I claim is:

An ink applicator comprising the combination of an ink container of two piece construction having bottom, side and end walls and a separately made top wall cover seated on and sealed to the upper edges of said side and end walls, one of the side walls of the container having an integrally formed upward extension the opposite ends of which terminate inwardly of the container end walls, and

a flat wick within said container, said wick extending upwardly along said extension of said side wall backing the wick and having locating openings therein, said cover having an integrally formed upstanding flange along an edge adjacent said one of the side walls and including a recessed portion conforming to three sides of the wick section and receiving the wick and the side wall extension therein, the face of the side wall extension adjacent the recessed portion of the flange of the cover being spaced therefrom to form a constricting passage for the wick encompassed by and passing therebetween, whereby the porosity and capillary action of the wick are decreased and spillage avoided, said cover further having a pair of integrally formed locating pins projecting from the recessed portion thereof through said wick locating openings and

engaging said extension of the adjacent side wall of the container to locate and limit displacement of said wick.
